UNITED STATES PATENT OFFICE.

LOUIS P. DISS, OF ILION, NEW YORK, ASSIGNOR TO THE WYCKOFF, SEAMANS & BENEDICT, OF SAME PLACE.

TYPE-WRITING MACHINE.

SPECIFICATION forming part of Letters Patent No. 614,244, dated November 15, 1898.

Application filed May 13, 1898. Serial No. 680,537. (No model.)

To all whom it may concern:

Be it known that I, LOUIS P. DISS, a citizen of the United States, and a resident of Ilion, in the county of Herkimer and State of New York, have invented certain new and useful Improvements in Type-Writing Machines, of which the following is a specification.

The line-spacing mechanism of a type-writing machine comprises, usually, a ratchet-wheel secured to one end of a cylindrical platen, a pawl for turning said ratchet-wheel tooth by tooth, and a detent or holdfast for insuring regularity of spacing and for preventing the platen from turning accidentally during the time of writing. In most machines the construction is such that the platen may also be rotated independently of the line-spacing pawl; but in such cases, as well as when the line-spacing pawl is actuated to rotate the platen, the latter is turned step-by-step distances equal to the distance apart of the spaces between the teeth of the ratchet-wheel, and hence the ordinary construction is not well adapted for printing upon ruled lines which are spaced apart differently from the tooth-spaces of the ratchet-wheel or for writing upon printed sheets having blank spaces to be filled or written in with the type-writer.

It is one of the objects of my invention to provide a means whereby the platen may be rotated independently of the line-spacing mechanism through any desired arc, minute or large, so as to bring any desired line or space on the sheet being written to the printing-point; and it is a further object of my invention to provide a simple and effective contrivance for releasing the platen ratchet-wheel from its detent and to simultaneously apply a means for preventing the platen from rotating too freely and for holding it firmly in any position to which it may be adjusted or turned during the course of the writing and quite as effectually as if the detent itself were in engagement with said ratchet-wheel.

To these ends my invention consists in the various features of construction and combinations of devices hereinafter more fully described, and particularly pointed out in the appended claims.

In the accompanying drawings, Figure 1 is

a side elevation of the carriage of a Remington type-writing machine embodying my improvements, the parts being in their normal positions. Fig. 2 is a plan view of the same. Fig. 3 is a view similar to Fig. 1, but showing the detent as having been disengaged from the platen ratchet-wheel and the friction brake or shoe as applied to the platen. Fig. 4 is a detached bottom plan view of the 55 detent, its spring, the brake-shoe and its pivoted frame or carrier, and the cam-lever by which the detent is removed from the ratchet-wheel and the brake-shoe applied to the platen; and Fig. 5 is a detached view of the 60 parts shown in Fig. 4, but looking at them in the direction of the arrow at the line *zz*, Fig. 1.

In the various views the same part will be found designated by the same numeral of reference.

70

1 designates the platen carriage or frame, in the side bars of which is journaled the platen-axle 2 in the usual manner.

3 is a cylindrical platen which at one end is provided with a line-spacing ratchet-wheel 75 4, adapted to be turned step by step by the usual line-spacing pawl 5. At 6 is secured to the platen-frame by a screw one end of a bar or leaf spring 7, which is forked at its opposite end and provided with bearings 8 for the 80 pivot-pin 9 of a detent 10, which in this instance is in the form of a small antifriction-roll capable of revolving freely on its pivot, although any other suitable form of detent may be employed.

85

11 represents a sheet-metal frame having downwardly-projecting ears 12, which are perforated to receive the pivot-pin 9, the ears 12 being arranged outside of or straddling the forked bearings 8 of the spring 7. At the rear 90 end of the frame 11 is a brake-shoe or friction-plate 13, which extends laterally inwardly over the platen and is supported by or formed integral with an arm or extension 14, projecting rearwardly from the inner one of the two 95 downwardly-projecting ears 12. The arm or extension 14 and the shoe or plate 13 are arranged at right angles to each other.

The forward end of the frame or device 11 is bifurcated and formed with eyes or bearings 15 to receive a pivot-pin 16, which also passes through a perforation in a cam or ec-

centric 17, arranged within the forks of said bifurcated portion. Said cam or eccentric is provided with a handle portion 18 for convenience of manipulation.

5 Rigidly secured to one of the side bars of the platen-frame and extending upwardly therefrom is a bracket 19, that is provided at its upper end with an inwardly-extending pin 20, upon which the cam or eccentric face 21 of the device 17 acts in the operation of the contrivance, as will be presently explained, and the said pin is also adapted to receive a notch or cut-away portion 22 on the cam or cam-lever for the purpose of locking or holding the detent out of engagement with the ratchet-wheel and the shoe or brake in engagement with the platen.

Referring to Figs. 1 and 2, the detent-roller is shown as in working engagement with the 20 ratchet-wheel and the brake or friction shoe as out of contact with the surface of the platen, while the actuating lever or device 17 is shown as swung backwardly and with its cam portion or face 21 resting lightly upon 25 the pin 20. With the parts in the positions shown and described the line-spacing mechanism may be said to be in normal condition, and when the line-spacing lever 23, carrying the pawl 5, is actuated the ratchet-wheel 30 and the platen will be rotated equal distances or distances equal to the spaces of the ratchet-wheel with which the detent-roller under the pressure of its springs 7 coöperates to hold the platen against accidental rotation during the period of writing after the 35 completion of the line-spacing movement. In this normal condition of the mechanism the shoe or plate performs no office whatsoever. When, however, it may be desired to turn the 40 platen irregular or ununiform distances and to hold the same firm for printing purposes, the said shoe or plate is brought into action and simultaneously the detent is thrown out of operative relation to the ratchet-wheel. 45 This is accomplished by one movement of the cam-lever. By pulling the handle portion 18 forward or to the position shown at Fig. 3 the cam portion proper, 21, riding upon the pin 20, operates to rock the sheet-metal frame 50 about the pivot 9 and to throw the shoe or plate 13 down upon the surface of the platen, and it also operates, after the shoe or plate has come to a bearing, to cause the detent to move up out of engagement with the ratchet-wheel, the spring 7 yielding or bending under the force applied to lift the detent, and this flexing of the spring acts to give it more tension and to cause the brake or plate to bear harder upon the surface of the platen. 55 When the detent has been lifted sufficiently above the ratchet-teeth and the brake has come to a proper bearing upon the platen, the notched portion 22 of the cam engages with the pin 20 and coöperates therewith to 60 lock or hold the parts in their new positions, as shown clearly at Fig. 3. From this view

it will be understood that the platen may be turned by its hand-wheel 24 freely in either direction and for any desired distance or through a large or very small arc, so as to 70 bring the desired point or place upon the paper exactly to the printing-point, and that the pressure or friction of the brake or plate upon the platen will serve to properly hold the platen in its adjusted position against accidental turning and quite as effectually as if the detent itself were coöperating with the ratchet-wheel. When the necessity for irregular spacing no longer exists, the detent 75 may be readily restored into engagement 80 with the ratchet-wheel by a simple backward movement of the handle portion 18 of the cam-lever to the position shown at Fig. 1, during which the spring 7 will coöperate to reengage the detent with the ratchet-wheel. 85

While I prefer to make the arm that carries the detent of elastic or springy metal, it will nevertheless be understood that the said arm may be made inelastic and that a separate spring may be provided for said arm, which 90 then may be pivoted as is common in various styles of type-writing machines.

The frame 11 acts as a lever during the operation of lifting the detent, the platen acting as a bearing or fulcrum for the plate or shoe 13 of said frame while the forward end of the frame is being lifted to raise the roller and flex its spring-arm.

Although I prefer to have the plate or shoe work or bear directly on the rubber surface 100 of the platen, it may be arranged to work on the metallic platen-head 25 between the core of the platen and the ratchet-wheel, or at any other suitable place, as long as it operates to put friction on the platen in substantially 105 the manner shown and described.

Various changes in detail, construction, and arrangement may be made without departing from the spirit of my invention.

What I claim as new, and desire to secure 110 by Letters Patent, is—

1. In a type-writing machine, the combination of a platen, a line-spacing ratchet-wheel, a spring-pressed detent therefor, and a lever-frame having a brake-shoe and connected to 115 said detent, whereby when the lever-frame is vibrated in one direction and the brake-shoe comes to a bearing on the platen the said detent is removed from the ratchet-wheel by a further movement of said lever and friction 120 or pressure is put upon the platen.

2. In a type-writing machine, the combination of a platen, a line-spacing ratchet-wheel, a spring-pressed detent, a lever-frame connected thereto and carrying a brake-shoe, 125 and a cam for vibrating said lever-frame and simultaneously disengaging the detent from its ratchet-wheel and causing the brake-shoe to press upon the platen.

3. In a type-writing machine, the combination of a platen, a line-spacing ratchet-wheel, a spring-pressed detent, a lever-frame con-

nected thereto and carrying a brake-shoe and a cam, and a projection or abutment on the framework for said cam to act against.

4. In a type-writing machine, the combination of a platen, a line-spacing ratchet-wheel, a spring-pressed detent, a lever-frame connected thereto and carrying a brake-shoe and a notched cam, and a pin on the framework for the cam to act against to lock the detent 10 out of engagement and the shoe into engagement.

5. In a type-writing machine, the combination of a platen, a line-spacing ratchet-wheel, a spring-arm carrying a detent-roller, a lever-frame connected to the pivot of said roller and provided at one end with a brake-shoe and at its opposite end with a cam, and a relatively-fixed projection for said cam to act 15 against.

20 6. In a type-writing machine, the combination of a platen, a line-spacing ratchet-wheel, a spring-arm provided with a roller-detent, a lever-frame mounted to turn on the pivot of said roller-detent and provided at one end 25 with a brake-shoe and at its other end with a cam-lever, and a relatively-fixed pin for the said cam-lever to act against.

7. In a type-writing machine, the combination of a platen, a line-spacing ratchet-wheel, a 30 spring-pressed arm carrying a detent, a frame

pivotsly connected to said spring-pressed arm and provided with a brake-shoe, a cam acting first to vibrate said lever and bring said brake-shoe into engagement with the platen and then to remove said detent from 35 the ratchet-wheel against the tension of the detent-spring and while the lever-frame is fulcruming on the platen at the brake-shoe.

8. In a type-writing machine, the combination of a platen, a line-spacing ratchet-wheel, a spring-pressed detent, a lever pivotally connected thereto and provided with a brake-shoe, a cam for moving the brake-shoe toward and against the platen and the detent away 40 from the ratchet-wheel, and a projection or 45 abutment for the cam to act against.

9. In a type-writing machine, the combination of a platen, a line-spacing ratchet-wheel, a spring-arm carrying a roller-detent, a lever-frame provided at one end with a brake-shoe 50 and at its opposite end with a lever, and a projection or abutment for the said lever to act against.

Signed at Ilion, in the county of Herkimer and State of New York, this 11th day of May, 55 1898.
